FIG. 5

UNITED STATES PATENT OFFICE

2,675,440

MAGNETIC SWITCH

Harry Reifel, Waltham, Mass., assignor to
Stevens-Arnold Inc., South Boston, Mass.

Application July 22, 1950, Serial No. 175,385

4 Claims. (Cl. 200—90)

1

This invention relates to electro-magnetic devices having vibrational, contact closing armatures, such as relays and choppers.

This invention provides an electro-magnetic device such as a chopper, which has the advantages over prior such devices, that its armature does not bounce when it strikes its associated fixed contacts, and that its armature is easily removable and replaceable, and is easily adjustable.

An object of the invention is to reduce the bouncing of a vibrational armature when it strikes an associated contact.

Another object of the invention is to provide for the adjustment of the position of a contact on a vibrational armature.

Another object of the invention is to provide for the easy removal of, and replacement of, a vibrational armature in an electro-magnetic device.

Another object of the invention is to provide for the adjustment, exterior of an electro-magnetic device, of a vibrational armature within the device.

The invention will now be described with reference to the drawing, of which:

Fig. 1 is a side elevation of a chopper embodying this invention;

Fig. 2 is a side elevation, in section, of the chopper;

Fig. 3 is a side elevation of the armature of the chopper;

Fig. 4 is a sectional view along the lines 4—4 of Fig. 2, and

Fig. 5 is a view looking at the left-hand end of Fig. 1 with the end disc removed.

The chopper has a central brass tube 10 having a circular flange 11 formed on one end and having the circular flange 12 threaded onto its other end. The tube 10 has a central cylindrical opening 13 for the reception of the vibrational armature 14 of magnetizable, spring metal.

The circular insulating disc 15 is in contact with the outer surface of the flange 11 and extends between same and the aligned inner sides of the brass bar 16 and the ceramic support 17.

The support 17 has a central, vertically extending slot in which are placed the contact plates 19 and 20 of magnetizable metal which are spaced apart by the insulating spacer 21. The plates 19 and 20 have their outer ends 22 and 23 respectively, extending perpendicular thereto and to which are attached the wires 24 and 25 respectively, for connecting the chopper in a circuit to be controlled.

2

The circular insulating disc 26 is in contact with the outer surfaces of the contact plate ends 22 and 23 and extends between same and the legs of a permanent magnet 27 which is fitted in a recess in the support 17. The circular brass disc 28 having a bent-over upper portion 29 extending perpendicular thereto, is secured to the support 16 by the screws 30, the support 17 having a flat upper surface 31 on which the disc portion 29 and the outer portions of the bar 16 are seated.

The screws 32 extend through the assembly including the brass disc 28, the support 17, the insulating discs 26 and 15, and are threaded into the flange 11, and secure this assembly to the

15 flange. The bar 16 has a central portion 33 which is seated upon the upper surface of the upper contact plate 19, and has the screws 34 extending through its outer portions and threaded into the support 17, the bar thus supporting the contact plates 19 and 20 in position and spaced apart by the insulating spacer 21.

The cylindrical armature supporting rod 35 which has a diameter slightly less than that of the opening 13 in the tube 10 so that it fits snugly into such opening, is cut away at its inner end to form a flat surface to which the outer end of the armature 14 is attached as by spot welding. The outer end of the rod 35 is slotted at 36 for receiving the blade of a screwdriver. The circular flange 37 which has a diameter equal to that of the tube 10, is formed on the rod adjacent its slotted end.

The armature 14 has the spaced apart, contact making, spring strips 37 and 38 of magnetizable metal, with the contacts 39 and 40 respectively, thereon, attached to its inner end as by spot welding, and between its inner and outer ends has the aligned spring strips 41 and 42 attached at their centers, as by spot welding, to the opposite sides of the armatures. The strips 41 and 42 are bowed outwardly between their centers and ends so that they contact the armature only at their centers and ends.

45 The flange 12 is threaded onto the tube 10 far enough to provide a space between the threaded end of the tube and the outer surface of the flange 12 which has a width slightly less than the thickness of the flange 37 on the armature supporting rod 35. The flange 12 is slotted at one side, and is recessed adjacent the slit for receiving the screw 38 which tightens the flange 12 on the tube 10 for locking it against further rotation. The rod 35 is inserted in the opening 13 in the tube 55 10 so that the outer, vertical surface of its flange

37 extends slightly outwardly beyond the flat, vertical, outer surface of the flange 12. The circular brass disc 42 has a central opening through which the outer end of the tube 35 extends, and which has a diameter slightly larger than that of the flange 12. It is placed against the outer surface of the flange 12 with the outer end of the rod 35 extending through its central opening, and is secured to the flange 12 by the screws 43 which are threaded thereinto, and which pull-up the washer 42 tightly against the flange 37 in the tube for preventing any turning of the armature.

When the armature rod is secured as described in the foregoing, the armature strips 39 and 40 are positioned between the inner ends of the contact plates 19 and 20 with contacts thereon in alignment with the contacts 39 and 40 on the contact strips. The magnetic field flows through the strips instead of across the gap between the plates 19 and 20.

The spring washer 44 is in contact with the inner, vertical surface of the flange 12, and extends between same and the insulating disc 45, the vertical inner surface of which contacts one end of the metal tube 46, the other end of which contacts one vertical side of the insulating disc 41, the other vertical side of which contacts the vertical surface of the flange 11 opposite to its vertical surface which contacts the insulating disc 15.

The tube 46 has outwardly turned ends, the inner surfaces of which fit against the outer surfaces of the metal circular plates 43 and 49, against the inner surfaces of which are fitted the outer surfaces of the circular insulating discs 50 and 51. The coil 52 of insulated wire is wound around the tube 46 between the discs 50 and 51, and has the ends 53 and 54 for connection to an alternating current source for energizing the chopper as will be described later in this specification.

In assembling the armature within the chopper, the screws 43 are left sufficiently loose that the armature supporting rod 35 can easily be turned by a screwdriver inserted in its slot 36. An oscilloscope is connected to the wires 24 and 25, and alternating current at the selected operating frequency is applied to the coil 52. The rod 35 is then turned slightly, first one direction, and then another, until the pattern on the oscilloscope shows the desired, uniform make-and-breaks. The screws 43 are then pulled up tightly for locking the armature rod in position.

The spring contact strips 39 and 40 can easily be bent by hand for providing the desired contact spacing.

In operation, alternating current which may be within the range of from 2 to 800 cycles per second in the embodiment of the invention illustrated, is applied through the wire ends 53 and 54 to the coil 52. This alternating circuit magnetizes the armature 14 so that it has first one and then the opposite polarity. The contact plates 19 and 20 are magnetized by the magnet 27 and each attracts and repels the free end of the armature during alternate half-cycles, causing the device to operate as a single-pole, double-throw switch. The armature would be connected in the circuit as would be the contact plates 19 and 20, the armature thus being electrically connected, first to one and then to the other of

the contact plates as is usual in choppers of this type.

By way of example, the chopper may be used to convert the weak direct currents from a thermocouple into alternating currents for amplification by a vacuum tube amplifier.

The free end of the armature tends to bounce when it strikes the contact plates, and this, if permitted, would result in erratic performance. Such bouncing is effectively damped out by the spring strips 41 and 62. The free ends of the strips touch the armature on the opposite sides thereof and oppose any longitudinal vibration thereof such as would result from bouncing of the armature end.

While one embodiment of the invention has been described for the purpose of illustration, it should be understood that the invention is not limited to the exact apparatus and arrangement of apparatus illustrated, since modifications thereof may be suggested by those skilled in the art without departure from the essence of the invention.

What I claim as my invention, is:

1. An electromagnetic device comprising a cylindrical tube, an energizing coil of wire around said tube, spaced apart contact plates at one end of the tube, an armature supporting rod having a cylindrical portion with a diameter slightly less than the inner diameter of said tube fitted into the other end of said tube, a flexible armature of magnetizable spring metal attached at one end to the inner end of said rod and having its other end between said plates, contacts on said other end of said armature between said plates, said cylindrical portion having an outer portion accessible from the exterior of said device for permitting rotation of said rod for properly positioning said contacts between said plates, and locking means at said other end of said tube and accessible from the exterior of said device for securing said rod against movement.

2. A device as claimed in claim 1 in which the rod has a flange in contact with said other end of said tube, and the means for securing the rod against movement includes a member threaded on said other end of said tube, and having an outer portion extending around the flange, and includes a disc around the rod in contact with the flange and attached to said member.

3. A device as claimed in claim 1 in which the contacts are strips of spring metal attached to the opposite sides of the armature, and have free ends extending towards the contact plates.

4. A device as claimed in claim 1 in which the armature has vibration dampening means comprising spring strips secured at their longitudinal centers to the opposite sides of the armature, and having free ends contacting the armature and being bowed away from the armature between their centers and ends.
